LEONHARD J. ROSBACH, OF BROOKLYN, NEW YORK.

CENTERING DEVICE.

Application filed March 19, 1921. Serial No. 453,838.

To all whom it may concern:

Be it known that I, LEONHARD J. ROSBACH, a citizen of the United States of America, residing at the city of New York, borough 5 of Brooklyn, county of Kings, and State of New York, have invented certain new and useful Improvements in Centering Devices, of which the following is a specification.

My invention relates to a centering device, and particularly to a tool for aligning or truing machine centers. The object of my invention is to provide a simple, rugged and serviceable appliance which, upon engagement between the centers, serves, by its 15 indications, to disclose the relation thereof.

In the accompanying drawings—

Fig. 1 is a broken plan of a tool in which my invention is embodied in one form;

Fig. 2 is a similar view with cover plate 20 removed, and showing the indicator elements in different position; and

Fig. 3 is a longitudinal section through the tool.

While the invention is susceptible of embodiment in various modified forms, I have shown it as a handy bench tool, comprising a rugged, generally cylindrical body member 5 adapted to be interposed between coned lathe members 6 and 7 of the usual type used 25 in metal working. These centers have the standard 60° cone shape universal in lathes of different makes, and the present tool, which cooperates with these centers, is thus substantially universal in its utility for all 30 machines having such centers.

As is common in machines of this type, one of the centers, 6, is fixed, while the other center, 7, is adjustable both longitudinally and transversely of the machine bed. The 40 alignment of these centers has been a more or less tedious operation, and repeated tests have generally been required before exact adjustment is secured. The present device provides a tool which may be readily secured 45 between the centers, after which the movable center 7 is adjusted into alignment with the fixed center 6 in accordance with the indications on the tool.

To receive the center 6 of the machine, the 50 body member 5 is socketed at one end at 8 to receive a closely fitting plug 9 having a cone bearing 10, in which the center 6 exactly fits. This plug 9 is preferably cushioned in the socket 8 against a spring 11 in order that a certain amount of play may be 55 permitted without injury to the tool when

the adjustable center 7 is moved up into engagement with it. A retaining pin 12 working in a groove 13 in the plug prevents the escape of the latter from the socket 8. 60 While the center bearing 10 need not be cushioned, I prefer the spring supported plug construction indicated by reason of the factor of safety thereby provided against 65 injury to the tool during use.

A bearing for the adjustable lathe center 7 is provided at the opposite end of the tool by a floating plug 14, similarly coned at 15 to form a socket in which precisely fits the coned end of the center 7. The plug 14 is 70 accommodated in a counterbore 16 in the body of the tool, and is pivoted therein on a vertical axis between the stud bearing 17 and the adjustable bearing pin 18.

The indicator mechanism is mounted in a 75 channel 19 cut in the upper face of the body 5 and communicating with an incline 20 on which are cut the graduations 21. Traveling over this scale is a needle pointer 22 engaged by an intermediate lever 23, which in turn is 80 engaged by an arm 24 rigid with the floating plug 14. In the construction shown the pointer 22 is carried by a hub 25 having centers 26 and 27 on which it is pivoted. The center 27 engages an adjustable bearing 28. 85 Coiled around the hub and engaging the same at one end is a coil spring 29, the opposite end of which is gripped by a clamp pin 30 driven into a hole in the body 5. This spring is normally under slight tension, sufficient to shift the pointer 22 to the 90 position indicated in Fig. 1; that is to say, out of the position which it occupies when the centers 6 and 7 are aligned. On the opposite side of its axis the pointer is provided with a lug 31 freely engaged on one 95 side by the lever 23. The latter is pivoted at 32 eccentrically on an adjusting disk 33, which is secured by the screw 34 in fixed position on the base when the parts have 100 been properly adjusted for accurate aligning indication. On the opposite side of its axis is a lug 35 freely engaged by the arm 24 of the floating plug 14.

In order to adjust the pointer 22 in exact position for center alignment indication, it is only necessary to place the tool between two properly aligned centers and to rotate the disk 33 until the incidentally changed position of the lever 23 brings the 105 pointer 22 into precise position with relation to the zero mark of the scale. The 110

tool is now trued for proper indication and the disk may be fixed in position by setting down hard the screw 34.

In order to house-in the levers, I provide a cover plate 36 seated on ledges 37 on opposite sides of the channel 19 and secured in position by screws 38, which take into suitable holes 39 tapped in the body 5 of the tool. This plate is also provided, preferably, with an end flange 40 corresponding to the end contour of the body and serving to house-in the floating plug 14 in its counter-bore 16. The adjustable center 7 has access to the cone seat in the plug through the large port 41 in the end flange. As a matter of convenience I form bearings on the inner face of the cover plate for the center 26 of the indicator lever 22, while the center 17 for the floating plug is mounted in the cover by a drive fit. Should there be any tendency to bind at these bearings when the cover piece is secured in position, the adjustable bearings 18 and 28 take care of this condition.

The tool normally assumes the position shown in Fig. 1. In operation it is placed against the fixed center 6, and the movable center 7 is then brought up into engagement with the floating plug 14. This engagement should be snug, and this is rendered possible without injury to the tool by the sliding block 9. In Fig. 1 the adjustable center 7 is shown (in full lines) out of alignment with the fixed center 16. When the center 7 has been socketed in the seat of the floating plug 14, its non-alignment with the fixed center 6 will cause the indicator to swing to the opposite ends of the scale (as indicated in dotted line in Fig. 1.) By transverse adjustment of the center 7 on the machine bed, however, the lever system 24, 23 and 22 will be brought to the position shown in Fig. 2, in which the pointer registers with the zero mark. In this position the centers are aligned and the tool may be removed.

If it is desired to ascertain whether or not the fixed center 6 is running perfectly true, the tool may be reversed in position and the center 6 rotated. If it is not running true it will cause the floating plug 14 to oscillate, and this will be indicated by the pointer 22. The center 6 may be then ground until, upon retest, the pointer holds its position without vibration while the center is rotated.

It will of course be understood that the connections between the floating socket and the pointer may be of any suitable character. The lever system shown is good because the spring 29 insures against lost motion between the levers, while at the same time affording free play, and the magnifying action of the levers renders the tool sensitive to slight angular variations, or

angular positions of the floating socket 14. Similarly the particular method of mounting the levers may be varied in different ways, and the cover plate may be substituted by some other construction.

Various other modifications will occur to those skilled in the art in addition to those above suggested, without departing from what I claim as my invention.

I claim—

1. In a centering tool, a supporting frame, a center receiving socket at one end thereof, a second center receiving socket mounted for angular displacement at the other end of the frame and having a socket recess extending across the axis of the socket support, together with indicating means actuated by the movement of said angularly displaceable socket.

2. A centering tool comprising a frame, a center receiving socket at one end thereof cushioned to permit longitudinal displacement thereof, but held against angular movement, and a second center receiving socket mounted at the other end of the frame and angularly displaceable with relation to said cushioned socket, in combination with indicator means associated with said angularly displaceable socket.

3. A centering tool comprising a frame, a pair of oppositely faced center receiving sockets therein adapted to axial alignment, one of said sockets being angularly displaceable with relation to the other and having its socket recess extending across the axis of its support, in combination with an indicator device associated with said angularly displaceable socket and serving to indicate the axial alignment of said sockets.

4. A centering tool comprising a frame, a pair of oppositely faced center receiving sockets arranged at opposite ends of the frame and adapted to axial alignment, one of said sockets being angularly displaceable with relation to the other, means for holding said angularly displaceable socket normally out of axial alignment with the other socket, in combination with an indicator device associated with said angularly displaceable socket and serving to indicate the axial alignment of said sockets.

5. A centering tool comprising a frame, a centering receiving socket angularly displaceable in said frame, an indicator lever operatively associated with said socket, a cooperating center-receiving socket in the frame, and spring means biasing said lever in one direction.

6. A centering tool comprising a frame, a center-receiving socket therein fixed against angular displacement, a cooperating oppositely-faced center-receiving socket susceptible of angular displacement in the frame, means associated with said angularly displaceable socket for indicating the axial

alignment of said socket, and spring means biasing said indicator means and associated socket out of socket-aligned position.

7. In a centering tool, a support, a center-receiving socket fulcrumed in said support, and having a center-receiving recess extending across the fulcrum axis of the socket.

8. A centering tool comprising a frame, a center-receiving socket fulcrumed on said frame, an indicator lever system mounted on said frame and associated with said socket, said lever system comprising a pivoted lever, and a pivoted support for said lever, said support being pivoted on an axis eccentric to the lever axis, for the purpose set forth.

9. A centering tool comprising a frame, a center-receiving socket fulcrumed on said frame, a multiplying lever system mounted in said frame and operatively associated with said socket, and spring means prevent-

ing lost motion between the elements of said lever system.

10. A centering tool comprising a casing, and mounted in one end thereof a spring supported plug having a center-receiving recess, together with means for holding said plug against escape and against angular displacement with respect to the casing in combination with an angularly displaceable center-receiving member mounted in said frame for axial alignment with the center recess in said spring-supported plug, and means operatively associated with the angularly displaceable center-receiving member for indicating the axial alignment of said center-receiving recesses.

In testimony whereof I have signed my name to this specification.

LEONHARD J. ROSBACH.
